UNITED STATES PATENT OFFICE.

FREDERICK T. SNYDER, OF OAK PARK, ILLINOIS.

ELECTRIC SMELTING-FURNACE.

1,254,079.

Specification of Letters Patent. Patented Jan. 22, 1918.

Application filed March 1, 1917. Serial No. 151,719.

To all whom it may concern:

Be it known that I, FREDERICK T. SNYDER, a citizen of the United States, residing at Oak Park, in the county of Cook and State 5 of Illinois, have invented a certain new and useful Improvement in Electric Smelting Furnaces, of which the following is a full, clear, concise, and exact description.

This invention relates to improvements in 10 electric smelting furnaces and more particularly to an improved ore feed adapted for use in connection therewith.

Heretofore it has been common in electric shaft furnaces for the lower surface of the 15 column of ore, as it gravitates into the melting chamber of the furnace, to be fused, due to the intense heat, into a solid crust or arch, which acts as a barrier and prevents the ore above it from feeding down. This causes 20 considerable delay in the melting process. Furthermore, this crust formation or arch, when broken by the increased pressure brought to bear thereon, causes the entire column to drop to the bottom of the furnace 25 with great force, resulting in an intermittent feed and giving rise to possible damage to the furnace.

The present invention aims to overcome the 30 various disadvantages caused by the arching of the ore, which is common in furnaces as now constructed, and has for its primary object the provision of means whereby the charge is fed into the furnace from the sides thereof, in such manner as to 35 prevent arching. Another object of the present invention resides in the provision of an electric smelting furnace which shall be provided with a roof, under which the charge is adapted to be fed.

40 A further object is the provision of means whereby the charge, prior to its introduction into the melting chamber of the furnace, is forced upwardly over an inclined surface to thereby permit the volatile met- 45 als, which rise from the molten slag in the form of gases and condense in the charge, as it is being fed in, to trickle down to said inclined surface through the charge and to be drawn off therefrom.

50 Other objects and advantages will be apparent from the following description, taken

in connection with the accompanying drawings, wherein the preferred embodiment of the invention is illustrated.

Figure 1 is a top plan view partly in section of an electric smelting furnace embodying my improvements.

Fig. 2 is a cross section taken on the line 2-2 of Fig. 1; and

Fig. 3 is a cross section taken on the line 3-3 of Fig. 1.

Referring more in detail to the drawings, the body of the furnace is shown at 1 and is provided with the usual refractory lining 2, a heat insulating lining 3 and an outer metallic shell 4. The melting chamber is indicated at 5 and is shown provided with the bottom contact 6, which in the present instance, is preferably a metal having a low melting point and a high boiling point, the 65 specific gravity of which is greater than the specific gravity of the metal being operated upon, in order that the same will remain in the bottom of the chamber 5 at all times. The metal used for this bottom contact 6 is 70 preferably lead. Leading from the chamber 5 to one side of the body of the furnace, is shown a passage 7, through which the molten metal forming the bottom contact flows into contact with the block 8, preferably composed of graphite. Connected with this block 8, is shown the copper lead 9, which conducts the current to the bottom contact 6, through the block 8, said block being provided to protect the end of the copper lead 75 from injury, which would be caused if the same was brought into direct contact with the molten lead. The tap hole of the furnace is shown at 10, through which slag is 80 drawn out through the spout 11. Above the body 1, is a suitable frame 12, in which is mounted the roof 13 of the furnace. Projecting through the roof 13 and terminating above the melting chamber 5 is the electrode 14, said electrode being preferably clamped 85 between suitable arms 15 projecting outwardly from the upright 16 and overhanging the roof of the furnace, substantially as shown. By means of suitable operating mechanism (not shown), said upright 16 100 may be raised or lowered to adjust the electrode 14 with relation to the bottom contact

6, as may be required. The roof 13 shown in the drawings is provided with a plurality of charging ports 17, through which the charge is fed into the furnace as hereinafter pointed 5 out. The frame 12 preferably extends above the top of the roof 13 as shown, in order that a considerable amount of ore may be supported above the furnace at one time. It will be noted from the foregoing that a roof 10 has been provided which may be readily removed from the body of the furnace, to thereby permit of easy access thereto for purposes of cleaning or repairing the same. It may be found more desirable in practice 15 to provide the roof 13 with a greater number of charging ports than is shown in the drawings, and accordingly, it is not intended to limit the present invention to any particular number of these ports, the right being 20 reserved to use a greater or less number than shown.

Mounted preferably below each of the charging ports 17 of the roof 13, are a plurality of feeders 18, shown pivoted at 19, 25 said feeders being adapted to be reciprocated in and out through the openings 20 provided in the side of the furnace, to push the charge into the melting chamber 5, as it gravitates down through said charging 30 ports. It will be noted that many different forms of mechanism may be devised to operate these feeders, and accordingly no particular form has been shown in the drawings, the right being reserved to use any 35 desired form of mechanism to accomplish this result. It is preferred to have the feeders 18 all working forward at the same time, in order that pressure exerted thereby will be balanced across the furnace.

40 During the melting operation in the furnace, should there be any volatile metals, for instance zinc, present in the ore, being fed into the furnace, the same will rise in the form of a gas when subjected to the heat 45 produced therein and will condense in the charge as it is fed in by the pushers 18. The top wall of the body of the furnace is preferably inclined downwardly away from the melting chamber 5, as shown at 20°. 50 It will be noted from this that the charge, after it has been fed through the charging ports 17, will be forced inwardly and upwardly over the inclined surface 20, by the feeders 18. This effectively prevents any 55 arching of the charge as it is fed into the melting chamber of the furnace for the reason that if a short arch forms, it will be concentric with the arc between the electrode and the charge and will therefore lack 60 the necessary upper abutment to enable it to resist pressure. A plurality of gutters 21 are positioned at the outer lower end of the inclined surface 20. This provides 65 means whereby the metal which has been condensed in the charge, may trickle down

through the same and into the gutter 21, thus separating said metal from the charge, as it is being forced by the feeders 18 into the melting chamber 5. From these gutters 21, the condensed metal is conducted 70 into a suitable trough 22, from whence it is drawn off through the outlet 23.

In practice, it has been found that certain grades of ore are so fine as to prevent the condensed metal from seeping through the 75 same and flowing down the inclined surface 20 and into the gutters 21. When such ore is encountered, it is preferred to make use of what may be termed column charging. As is well known, it is common to mix coke 80 with ore as the same is fed into the furnace in order to provide for the necessary reduction. According to the present invention however, when extremely fine ore is encountered, it is preferred to feed the ore and coke 85 into the furnace through the charging ports in separate columns. For instance, this may be accomplished by feeding a column of coke and a column of ore, through each of the charging ports, substantially as shown 90 in Fig. 3 of the drawings, the column of coke being positioned adjacent the outer wall of the frame 12. It will thus be seen that as the feeders 18 work inwardly, the coke is forced upwardly over the inclined surface 95 20 and into the melting chamber 5, thereby providing means whereby the condensed metal may gravitate therethrough and down said surface 20 into the gutters 21. If preferred, the column charging may be effected 100 by feeding coke through alternate charging ports and ore through the remaining ones. In other words, the column charging may be effected either radially or circumferentially.

It is obvious that various changes and 105 modifications may be made in the structure shown and described herein without departing from the spirit of the invention, and the right is therefore reserved to make such changes and modifications as fall within the 110 scope of the appended claims.

Having thus described my invention, what I claim as new and desire to secure by Letters Patent of the United States is:

1. The method of charging an electric furnace which consists in feeding the charge radially inward toward the arc from all sides, in a horizontal plane only. 115
2. The method of charging an electric furnace which consists in feeding the charge 120 down around the outer circumference thereof and inwardly and upwardly to the melting chamber.
3. The combination with an electric furnace body of a roof, an electrode projecting 125 through said roof, and means for feeding a charge into said furnace laterally under said roof toward said electrode whereby a free arc may be maintained between said electrode and said charge and the escape of 130

volatile constituents of the charge prevented by said roof.

4. An electric furnace comprising a body, a roof, an electrode projecting through said roof whereby an arc may be maintained between said electrode and the charge in the bottom of the furnace, and means for feeding the charge toward said arc from all sides whereby said charge is melted down 10 before reaching said electrode, thereby maintaining a free arc in the center of a crater.

5. An electric furnace comprising a base, lateral feeding means associated therewith, a frame removably supported on said base 15 and a roof carried by said frame, whereby said roof may be removed to expose said feeding means and the melting chamber.

6. An electric furnace comprising a body provided with a melting chamber, a roof 20 provided with a plurality of charging ports near the periphery thereof, and means adapted to force the charge radially inward toward said melting chamber, said charge being in contact with said roof adjacent 25 said ports to seal said melting chamber.

7. An electric furnace of the arc type, comprising a body, a melting chamber therein, the upper wall of said chamber being inclined downwardly away from the interior of said chamber, and means adapted 30 to force a charge of ore into said chamber over said inclined wall to permit of the separation of condensed metal therefrom.

8. An electric furnace of the arc type, comprising a body, a melting chamber therein, the upper wall of said chamber being inclined downwardly away from the interior of said chamber and means adapted 35 to force a charge into said chamber over said inclined wall to permit of the separation of condensed metal therefrom, and means to receive the metal thus separated.

9. An electric furnace comprising a body portion, a melting chamber positioned therein, said melting chamber being provided 45 with an upper wall inclined downwardly away from the interior of said chamber.

10. An electric furnace comprising a roof, a body portion, and reciprocating means interposed therebetween adapted to force a charge laterally into said chamber.

11. An electric furnace comprising a roof, a body portion, and means interposed therebetween adapted to force a charge laterally 55 into said chamber and into contact with the under side of said roof, to seal said chamber.

12. The method of charging an electric furnace, which consists in feeding a column of ore and a column of combustible material 60 downwardly near the outer circumference thereof and then forcing said charge laterally into the melting chamber in contact with said roof.

13. The method of charging an electric 65 furnace which consists in feeding radially

disposed columns of ore and combustible material downwardly into said furnace, said combustible material being outside of said ore and then forcing such charge laterally into the melting chamber.

70

14. The method of charging an electric furnace which consists in feeding radially disposed columns of ore and combustible material downwardly into said furnace and then forcing the same laterally in layers 75 into the melting chamber.

15. The method of charging an electric furnace which consists in feeding radially disposed columns of ore and combustible material downwardly into said furnace and 80 then forcing the same laterally in layers over an inclined surface into the melting chamber.

16. The method of charging an electric furnace which consists in feeding radially 85 disposed columns of ore and combustible material downwardly into said furnace and then forcing the same laterally in layers into the melting chamber, the layer of combustible material being disposed beneath the 90 layer of ore.

17. The method of charging an electric furnace which consists in feeding radially disposed columns of ore and combustible material downwardly into said furnace and 95 then forcing the same laterally in layers over an inclined surface into the melting chamber, the layer of combustible material being disposed beneath the layer of ore and 100 in contact with the inclined surface.

18. An electric furnace comprising a body portion, a frame mounted thereabove, a roof positioned within said frame and an electrode projecting through said roof.

19. An electric furnace comprising a body 105 portion, a frame mounted thereabove, a roof positioned within said frame and an electrode projecting through said roof, said roof and said frame being removable from said body portion.

110

20. An electric furnace provided with a refractory roof, a roof band supporting the same, means for feeding a charge laterally under said roof toward a melting chamber, and means for supporting said roof band, 115 whereby said roof may be removed to expose said chamber and said feeding means for inspection.

21. An electric furnace comprising a body portion, a frame, and a roof mounted within 120 said frame and above said body portion, said frame extending above said roof and adapted to coöperate therewith to support the material to be fed into said furnace.

22. An electric furnace comprising a body 125 portion, a roof mounted thereon, and a frame surrounding said roof and adapted to coöperate therewith to support the material to be fed into said furnace, said roof being provided with means adapted to per- 130

mit of said material being fed downwardly in columns around the outer circumference of said roof into said furnace.

23. An electric furnace having a roof provided with a charging port and a feeder arranged to force the charge laterally against the inner edge of said port, whereby said

port is sealed against the escape of gas therethrough.

In witness whereof, I hereunto subscribe my name this 26th day of February A. D., 1917.

FREDERICK T. SNYDER.
